UNITED STATES PATENT OFFICE.

ARTHUR E. DEMERS, OF SOUTHERIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

PITCH-POT.

1,378,528.

Specification of Letters Patent. Patented May 17, 1921.

Application filed November 10, 1919. Serial No. 337,062.

To all whom it may concern:

Be it known that I, ARTHUR E. DEMERS, a citizen of Canada, residing at Southbridge, in the county of Worcester and State 5 of Massachusetts, have invented certain new and useful Improvements in Pitch-Pots, of which the following is a specification.

This invention relates to improvements in pitch pots and has particular reference to a 10 pot of this character especially adapted for use in connection with the blocking of ophthalmic lenses.

The leading object of the present invention is the provision of an improved form of 15 pot which will facilitate the re-using of scrap and excess material and the quick and rapid softening or preparing in condition for use of fresh material without in any way interfering with or delaying the blocking 20 operations.

A further object of my invention is the provision of a novel and improved form of pitch pot which will insure usable thoroughly softened pitch only being accessible 25 to the operator, and eliminate the supplying of lumpy improper material to the blocker.

A further object of the present invention is the provision of an improved construction 30 of device which may be readily applied to pots now in use to enable the advantages of my improvement to be obtained without altering or remodeling thereof.

Other objects and advantages of my improved construction should be readily apparent by reference to the following specification taken in connection with the accompanying drawings, and it will be understood that I may make any modifications in the specific details of construction shown and 35 described within the scope of the appended claims without departing from or exceeding the spirit of my invention.

Figure I represents a plan view of a structure embodying my improvements.

Fig. II represents a vertical sectional view 45 as on the line II-II of Fig. I.

Prior to my present invention it has been customary in the blocking of lenses or similar work, to make use of a heated pot which 50 will maintain the pitch in a soft or melted condition so that it may be readily applied to the blocks for the lenses, it being understood that this pitch is used for an adhesive for securing lenses to metal or other forms 55 for subsequent grinding of the exposed por-

tion of the glass, this securing process being commonly termed blocking. The difficulty hitherto experienced has been due to the fact that with the ordinary heated pot the heat being applied to the exterior, the pitch along 60 the edges would be in good condition, but as the material was exhausted and fresh material added, the fresh material would tend to float in the center of the pot away from the source of heat, thereby melting very slowly 65 and continuously interfering with the dipping out of the desired soft material.

An additional objection resided in the fact that when excess pitch is used in the blocking it is desirable that the scraps be put 70 back into the kettle to be re-softened and re-used, these scraps having a tendency to get into the pitch being ladled out in the next operation and interfere with proper blocking.

I have, therefore, provided my present structure to obviate these several difficulties, to cause the new pitch or scraps of old pitch 75 as supplied, to be brought nearer the source of heat and thus more rapidly heated so that 80 the pot may be continuously fed and delays due to getting new pots of material or to melting an entire new pot eliminated and at the same time to insure only proper 85 softened pitch being supplied for the blocking operation.

For an understanding of my improvement I would refer to the accompanying drawings, in which the numeral 1 designates the table member having mounted therein the 90 pitch pot 2 whose edge preferably rests on the gasket 3 sealing the steam chamber 4 by which the pot is kept in heated condition to soften the interior pitch 5. In carrying out 95 my invention I preferably place within the pot 2 the vertical guides 6 between which slide my improved partition member 7 having the lateral wings 8 resting on the top of the pot to limit the downward movement of the slide partition 7 so that a space 9 is 100 provided between the bottom of the partition and the bottom of the pot. With this partition inserted within an ordinary pot, either with or without the guide ways 6 the lumps 10 of pitch may be placed on the one 105 side of the partition which will hold them relatively near the heated side of the pitch pot and prevent their floating to the center and remaining there in a semi-fluid rather than a proper fluid condition, the new mate- 110

rial all being added on one side of the partition, the weight of this material forcing the pitch from that side through the space 9 at the bottom of the partition into the opposite side of the pot from which the clear molten pitch may be dipped as required. To prevent excess waste during this dipping process the upper portion as at 11 projects slightly above the surface of the pot and provides a satisfactory central scraper on which the bottom of the dipper may be wiped as it is moved out of the pot to deliver the desired quantity of pitch.

From the foregoing description it will be seen that I have provided an improved partition device applicable to old or new pitch pots, which will divide the pot into two sections, one for the material being added and to be softened, and the other for the softened usable portion of the material, and which in addition provides a satisfactory scraper or wiper to remove the waste pitch from the bottom of the dipper being employed.

25 I claim:

1. An optical pitch pot comprising a container for the pitch, an inclosing member providing a heating chamber therefor en-

circling the container, said container having an exteriorly flared portion interlocking 30 with the inclosing member and having interiorly projecting ribs and a combination partition and scraper member having a depending portion spanning the pot and slidably received between the ribs and having laterally projecting portions engaging the flaring edge of the pot for limiting the downward movement of the partition, said member being further provided with an upwardly projecting scraper portion, substantially as illustrated.

2. A combined partition and scraper for a pitch pot comprising a main partition portion of size to substantially fit the pot transversely thereof, lateral projections adapted 45 to engage the edges of the pot to support the partition in spaced relation to the bottom of the pot, and a central portion projecting above the pitch level to provide a scraper.

In testimony whereof I have affixed my signature in presence of two witnesses.

ARTHUR E. DEMERS.
